UNITED STATES PATENT OFFICE.

JOHN B. TAYLOR AND DANIEL S. CARPENTER, OF SCHENECTADY, NEW YORK, ASSIGNEES
TO GENERAL ELECTRIC COMPANY, A CORPORATION OF NEW YORK.

PROTECTIVE DEVICE FOR ELECTRIC CIRCUITS.

No. 925,054.

Specification of Letters Patent. Patented June 15, 1909.

Application filed March 15, 1907. Serial No. 362,483.

To all whom it may concern:

Be it known that we, JOHN B. TAYLOR and DANIEL S. CARPENTER, citizens of the United States, residing at Schenectady, county of 5 Schenectady, State of New York, have invented certain new and useful Improvements in Protective Devices for Electric Circuits, of which the following is a specification.

10 Our invention relates to protective devices for electric circuits, and more particularly to such devices used in connection with telephone lines, especially those carried on the same poles as high-tension transmission lines 15 and exposed to the inductive effect of the currents flowing in the transmission line, as well as to excessive potential caused by lightning or by contact between the transmission line and the telephone line; and the object of our 20 invention is to provide a compact and reliable device which will protect the telephone and its user in case of any abnormal conditions upon the telephone line, regardless of the origin of such conditions.

25 In the preferred embodiment of our invention a movable member forming part of a switch by means of which the telephone circuit may be opened, carries a fuse for each line of the telephone circuit, a spark-gap connected between the two lines of the circuit, and a line-discharge terminal for each line of the telephone circuit coöperating with a 30 grounded discharge terminal adjustable with relation to the line discharge terminals.

35 The gap between the line discharge terminals and the grounded terminal may be adjusted so that it will break down only in case of a dangerous rise in potential on the telephone line caused by lightning or by a lead of the 40 transmission line coming into contact with the telephone line, while if an arc holds between a line terminal and the grounded terminal a fuse blows, and if for any reason this does not open the circuit the arc may be 45 broken by moving the support carrying the line terminals.

Our invention will best be understood in connection with the accompanying drawings showing one embodiment of our invention 50 merely for illustration, in which—

Figure 1 is a perspective view of our protective device; Fig. 2 a sectional view, showing the line-discharge terminals and the

spark-gap between the lines of the circuit; and Fig. 3 a diagram showing the relation of 55 the protective device to the telephone circuit; parts of the protective device being shown in elevation.

In the embodiment of our invention shown in the drawings, a base-block 1 carries insulators 2, and a terminal block 3 mounted on one insulator, carries clips 5, while terminal block 4 mounted on the other insulator carries clips 6. A movable member or tube 7, made of fiber or any suitable insulating material, carries at one end a pair of blades 8, one on each side of the tube, connected to the clips 6 by means of pivots 9, while a pair of blades 10, secured to the other end of the tube 7, one on each side thereof, coöperate 70 with the clips 5. Each of the blades 8 and 10 carries a fuse clip 11, and fuses 12, preferably of the inclosed type with the fuse-wire surrounded by refractory material, engage the clips and thereby establish electrical connection between the blades on each side of the tube 7. An operating ring or handle 13 is securely attached to the tube 7, and the whole structure forms a double-pole knife-blade switch swinging about the pivots 9, 80 each blade of the switch consisting of a blade 8, fuse 12 and blade 10, and coöperating with a clip 5 and a clip 6. By means of this switch the telephone circuit may be broken when desired. 85

In order to provide against excessive differences of potential between the two sides of the telephone circuit, a spark-gap 14, preferably consisting of two carbon blocks separated by a sheet of mica is mounted on the tube 7, as shown in Figs. 1 and 2, and is held in position between spring-clips 15, each of which is connected to one line of the circuit and makes an electrical connection between the line and one side of the spark-gap, as 90 well as forming a mechanical support to hold the spark-gap in position. An excessive potential on the lines of the telephone circuit is prevented by a spark-gap to ground, and the preferred form comprises line-discharge terminals 16 and 17, one mounted on each of the blades 8, and thereby connected to the lines of the circuit, and a ground-discharge terminal 18 coöperating with the line-discharge terminals 16 and 17, and mounted so 105 as to be adjustable transversely of the gap.

between the terminals 16 and 17. The grounded terminal 18 is carried in a supporting tube 19 connected to the ground and is held in adjusted position in said tube by means of a set-screw 20. The grounded terminal 18 is so adjusted with relation to the terminals 16 and 17 that an excessive potential on either line, due to lightning or to contact with a lead of the transmission line, will break down the gap and discharge to the ground; and any arc that may form between either terminal 16 or 17 and the terminal 18 will cause a fuse to blow, thereby opening the circuit; although if for any reason the fuse fails to open the circuit it may be done by moving the member 7 to lengthen the gap between terminal 18 and the other terminals.

The relation of the protective device to the telephone and to the telephone circuit is shown, for purpose of illustration only, in Fig. 3. The device is of great utility in connection with any telephone system, but is particularly useful in connection with a system such as shown in Fig. 3, in which a telephone 21 is connected to the primary 22 of a transformer, the line between the transformer and the telephone being protected by a spark-gap 23, which carries any excessive potential on the lines to the ground. The secondary 24 of the transformer is connected through the protective device to the lines 25 and 26 of the telephone circuit. The transformer is interposed between the telephone and the telephone lines to insure the protection of the user of the telephone against shocks, no matter what the potential of the telephone-line may be, while the protective device is inserted in the line beyond the transformer, so that abnormal conditions on the lines, such as result from the lines being struck by lightning or from being in contact with the leads of a high-tension transmission line, will not destroy the transformer and thereby bring the excessive potential of the telephone-line upon the telephone. In case, for any reason, an excessive current flows over the telephone circuit, the fuses 12 will blow, and thereby open the circuit; if there is an abnormal difference of potential between the two sides of the telephone circuit, the spark-gap 14 will break down and permit the difference of potential to be equalized; while if the potential of the telephone line in relation to the ground reaches an abnormal amount, either through the action of lightning or a direct contact of the telephone line with a high-tension system, the gap between the line-discharge terminals 16 and 17 and the grounded discharge-terminal 18 will break down, and the excessive potential will thereby be relieved. If the excessive potential is due to a direct contact between the transmission-line and the telephone-line, an arc would be maintained between the terminals

16 and 17 and the grounded terminal 18, which would soon destroy the apparatus. The rush of current caused thereby normally blows the fuses, thereby opening the circuit, but if for any reason the circuit is not opened when the arc forms the switch may be opened by means of the operating ring 13, lengthening the gap between the terminals 16 and 17 and the grounded terminal 18 to such an extent that the arc is broken and the device saved from destruction.

Our invention may be embodied in many other forms than the forms shown in the drawings, and we, therefore, do not wish to be restricted to the precise form shown and described; but intend to cover by the claims all changes and modifications which are within the spirit and scope of our invention.

What we claim as new and desire to secure by Letters Patent of the United States is,—

1. In a protective device for electric circuits, the combination with a switch having a movable blade for each side of the circuit, of a line discharge terminal mounted on each blade, and a grounded discharge terminal co-operating with both said line terminals when the switch is closed.

2. In a protective device for electric circuits, the combination with a switch comprising a base, switch clips secured thereto, a movable insulating support carrying metallic blades at each end for engaging said clips, and a fuse connecting said blades, of a line discharge terminal mounted on said insulating support, and a grounded discharge terminal co-operating with said line terminal when the switch is closed.

3. In a protective device for electric circuits, the combination with a switch comprising a base, two pairs of switch clips secured thereto, an insulating tube, a pair of blades secured at each end of the tube, the blades of each pair being on opposite sides of the tube and each blade co-operating with one of said clips, and a fuse on each side of said tube connecting the blades on that side.

4. In a protective device for electric circuits, the combination with a switch comprising a base, two pairs of switch clips secured thereto, an insulating tube, a pair of blades secured at each end of the tube, the blades of each pair being on opposite sides of the tube and each blade co-operating with one of said clips, a fuse on each side of said tube connecting the blades on that side, a pair of line discharge terminals carried by said tube, one on each side, and a grounded discharge terminal co-operating therewith when the switch is closed.

5. In a protective device for electric circuits, the combination with a switch comprising a base, two pairs of switch clips secured thereto, an insulating tube, a pair of blades secured at each end of the tube, the blades of each pair being on opposite sides of

the tube and each blade coöperating with one of said clips, a fuse on each side of said tube connecting the blades on that side, a pair of line discharge terminals carried by said tube, one on each side, and a grounded discharge terminal adjustable with relation to the line terminals and coöperating therewith when the switch is closed.

In witness whereof, we have hereunto set our hands this 13th day of March, 1907.

JOHN B. TAYLOR.
DANIEL S. CARPENTER.
